UNITED STATES PATENT OFFICE.

JOHN J. O'BRIEN, OF ST. LOUIS, MISSOURI.

TIRE MOUNTING AND DEMOUNTING TOOL.

1,197,758.

Specification of Letters Patent. Patented Sept. 12, 1916.

Application filed June 21, 1915. Serial No. 35,278.

To all whom it may concern:

Be it known that I, JOHN J. O'BRIEN, a citizen of the United States, and resident of St. Louis, Missouri, have invented certain 5 new and useful Improvements in Tire Mounting and Demounting Tools, of which the following is a specification containing a full, clear, and exact description, reference being had to the accompanying 10 drawings, forming a part hereof.

My invention relates to improvements in tools for mounting and demounting tires, and my object is to construct a simple, inexpensive and easily operated tool to expedite, and minimize the effort in, the 15 expansion and contraction of a rim in the mounting and demounting of pneumatic tires.

With the above object in view, my improvements consist in the novel construction and arrangement of parts, hereinafter fully described, pointed out in my claims and illustrated by the accompanying drawings, in which—

25 Figure 1 is an elevation of a tool embodying my improvements and a portion of a rim, shown in section, one set of the rim engaging devices being broken away; Fig. 2 is an elevation, taken at right angles to Fig. 1, showing the complete tool in a folded position; Fig. 3 is an elevation, taken at right angles to Fig. 1, showing certain of the parts in section; Fig. 4 is a sectional plan taken on the line 4—4 of Fig 1; Fig 5 is an inverted plan of the device as shown in Fig. 2; Fig. 6 shows my improved tool as applied to a rim in its expended or normal circular shape; and Fig. 7 is a view similar to Fig. 6 showing the rim contracted 40 to permit removal of the tire.

Referring by numerals to the accompanying drawings: 10 and 11 designate the body portions of the tool, each of which has at its one end a perforated ear 12 and an 45 ear 13, the ears 12 providing a hinging means for the bodies, whereby to permit folding when not in use and the ears 13 providing means together with a bolt 14 for locking the bodies against hinging when 50 alined or extended for use. At the said hinged end of each of the bodies 10 and 11 between the ears 12 and 13, and extending at right angles to the bodies, are the levers 15, which are preferably plano-convex in 55 cross section and disposed to combine to form a substantially cylindrical lever on

each side of the bodies when said bodies are alined. These bodies 10 and 11 are formed hollow, and at their free ends are internally threaded in opposite directions, that 60 is one has a right hand thread and the other a left hand thread to receive the threaded staffs 16 and 17.

In the outer end of each staff 16 and 17 there is a threaded seat 18, in which are 65 located the threaded stems 19, each of which has at its outer end a head 20, and wings 21, and on the outer face of each head there is a section 22 of material such as soft metal, which when brought to bear against 70 the rim will not mar the finish of the rim.

The staffs 16 and 17 are reduced in thickness between their threaded portions and the portions containing the seats 18 and perforated to receive rivets, on each of 75 which there is mounted a pair of tongs 23, each part of which tongs has at its free end a hook 24 which engages over the flange 25 of a rim and next adjacent the hook a shoulder 26 which prevents the hook from 80 extending too far over the rim flange to stand in the way of the tire in mounting or demounting, as well as to serve (in pairs) to hold the head 20 centered with relation to 85 the rim.

The numerals 27 designate collars, one of which is mounted for lengthwise movement on each stem 19 and as shown in Fig. 4, each is provided with a key-way, 90 which together with a key 28 formed integral with each stem prevents rotation of the collars. On each collar there are the diametrically opposite ears 29 and pivotally connecting each ear 29 with each part of the tongs 23 is a link 30. Each collar carries a set screw 31, whereby to secure the collars against lengthwise movement on the stems and by preference the faces of the keys 28 are provided with seats to receive the ends of the set screws. 95

As shown in Fig. 6 and 7, the tool is placed diametrically of the rim and is intended for use only on the rims of the non-continuous type which are to be distorted from their normal circular shapes to facilitate the freeing of tires therefrom. 100

In brief my tool is a turnbuckle having means at its ends for engaging a rim at diametrically opposite points to expand the rim from a contracted, non-circular, shape to a normal circular shape in the mounting of a tire, and a pair of tongs at each end of 110

the turnbuckle to hook over the rim for the purpose of contracting or distorting it from its normal circular shape to free at least a portion of it from the tire.

- 5 Assuming the tire to be placed on a rim, contracted or distorted from its normal circular shape, as shown in Fig. 7, the tool is placed as shown, and lengthened or shortened by its various threaded elements until 10 both heads 20 are brought to engage the inner perimeter of the rim, the one head engaging the rim near its break joint and the other head at a diametrically opposite point. The tongs are then swung on their pivots to 15 bring their outer, free, hooked ends to engage over the flanges of the rim, where they are locked through the links 30, collar 27 and set screw 31. This locking of the hooked tong ends to the flanges of the rim 20 not only prevents spreading of the tongs when in use but the locked tongs hold the heads centered on the rim, to the end that when outward pressure is applied to the heads through a manipulation of the turn- 25 buckle the heads will not slip laterally. The levers of the turn-buckle are then grasped and the two bodies rotated relative to the threaded staffs, and the tool as a whole lengthened out, thus spreading the rim to 30 circular shape. It is to be noted here that the tongs engaging the rim hold the threaded staffs against turning while the bodies are being turned, and that the keyed-collars relieve the links 30 from torsional strains.

35 The operation of contracting the rim is accomplished by placing the tool as described

and turning the bodies in a direction relative to the fixed staffs to shorten the tool and through the tongs contract the rim.

Having thus described my invention, what 40 I claim as new therein and desire to secure by Letters Patent of the United States is:

1. In a tool of the class described, a turn buckle, comprising a rigid body having oppositely internally threaded seats and a pair 45 of threaded staffs, a headed stem having a threaded connection with each staff, a pair of tongs carried by each staff and means for locking the tongs against movement.
2. In a tire mounting and demounting 50 tool, a turn buckle comprising a pair of rigid bodies having hinge connections at their one end and oppositely threaded seats at their other ends and a threaded staff in each seat, means for holding the rigid bodies 55 against relative movement when brought to alinement, a headed stem having threaded connection with each staff, a pair of tongs having hooks at their ends, pivotally connected with each staff, a collar keyed to each 60 stem and free to move lengthwise thereof, a set screw carried by each collar to lock it against movement relative its stem, and a link connection between each collar and each pair of tongs.

In testimony whereof, I have signed my name to this specification, in presence of two subscribing witnesses.

JOHN J. O'BRIEN.
